ELECTRIC KITCHEN MIXER GRINDER
ATTACHMENT

Robert F. Lindgren, Aurora, Ill., assignor to Daco
Incorporated, Aurora, Ill., a corporation of Illi-
nois

Application February 12, 1952, Serial No. 18,482

Term of patent 14 years

(Cl. D44—1)

To all whom it may concern:

Be it known that I, Robert F. Lindgren, a citizen of the United States, residing in the city of Aurora, county of Kane, State of Illinois, have invented a new, original, and ornamental Design for an Electric Kitchen Mixer Grinder Attachment, of which the following is the specification, reference being had to the accompanying drawing, forming a part thereof in which:

Figure 1 is a perspective view of the electric kitchen mixer grinder attachment showing my new design;

Figure 2 is an elevational view thereof;

Figure 3 is an end view as seen from the right of Figure 2;

Figure 4 is a top plan view; and

Figure 5 is an end view as seen from the left of Figure 2.

The dominant features of the design reside in the portions shown in full lines.

I claim:

The ornamental design for an electric kitchen mixer grinder attachment, substantially as shown and described.

ROBERT F. LINDGREN.
